(57) **CLAIM**

The ornamental design for a handle for mobile device, as shown and described.

DESCRIPTION

FIG. 1 is a front perspective view of a handle for mobile device showing our new design;

FIGS. 2 and 3 are, respectively, front and rear elevational views of the handle for mobile device of FIG. 1;

FIG. 4 is a right elevational view of the handle for mobile device of FIG. 1;

FIG. 5 is a left elevational view of the handle for mobile device of FIG. 1; and,

FIGS. 6 and 7 are, respectively, top and bottom plan views of the handle for mobile device of FIG. 1.

The broken line showing in the figures is for the purpose of illustrating environment and forms no part of the claimed design. The handle for mobile device is shown with a symbolic break in its length. The appearance of any portion of the article between the break lines forms no part of the claimed design.
